UNITED STATES PATENT OFFICE

MELBOURNE L. CARPENTIER, OF DETROIT, MICHIGAN, ASSIGNOR TO CHRYSLER CORPORATION, OF DETROIT, MICHIGAN, A CORPORATION OF DELAWARE

COOLING SYSTEM

Application filed February 1, 1930. Serial No. 425,330.

- This invention relates to an improved cooling system for internal combustion engines.
- The main objects of this invention are to provide a cooling medium jacket for the cylinders of an internal combustion engine which will circulate the major part of the incoming medium rearwardly to the end of the cylinder block before allowing it to contact with the cylinders; to provide an improved jacket of this kind which will circulate the main part of the cooling medium forwardly from in back of the rear cylinder; to provide an improved cooling system in which the main part of the incoming cooling medium flows directly along one side of the valve sleeves before it is heated by the cylinders so as to subject the valves and their associated members to the maximum cooling action of the medium; and to provide a partition in the cooling medium jacket having apertures which will permit some of the incoming medium to flow between adjacent valve sleeves in close proximity to the valve seats so as to concentrate the cooling action in the vicinity of the valve seats and to mix some of the incoming cooling medium with that part of the medium which has been heated during its incomplete forward travel in the cylinder compartment of the jacket.
- An illustrative embodiment of my invention is shown in the accompanying drawings, in which:
- Fig. 1 is a vertical section of an internal combustion engine embodying my invention.
- Fig. 2 is a front end elevation of an engine.
- Fig. 3 is a side elevation of the engine showing the radiator of its cooling system.
- Fig. 4 is a horizontal section taken on line 4-4 of Fig. 1.
- Fig. 5 is a vertical section taken on line 5-5 of Fig. 1.
- Fig. 6 is a vertical section taken on line 6-6 of Fig. 4.
- In the form shown, the engine includes a cylinder block having a plurality of cylinders and adjacent valve sleeves about which is formed a cooling medium jacket having an inlet passage and a cylinder compartment on the respectively opposite sides of the valve

sleeves. Webs joining adjacent sleeves form a partition between the inlet passage and the cylinder compartment which directs the incoming cooling medium, the rear of the block.

In the illustration shown, the internal combustion engine 1 comprises a plurality of cylinders 2 having an inlet valve sleeve 3 and an exhaust valve sleeve 4 in related proximity to each cylinder. Surrounding the cylinders and valve sleeves is a cooling medium jacket 5 which has an inlet 6 at its front end. A cooling medium pump having a rotor 7 is journaled in the inlet 6 and communicates with a radiator 8 through a tube 9.

Webs 10 are provided between the adjacent valve sleeves so as to form a partition within the water jacket between the inlet passage 11 and the cylinder compartment 12 thereof. This partition terminates in spaced relation to the rear end of the jacket and permits the cooling medium to flow into the cylinder compartment in back of the rear cylinder. Formed on the front exhaust valve sleeve 4 and on the front end of the jacket 5 are flanges 14 and 15 respectively, which coact with the rotor 7 in preventing the incoming cooling medium from entering the front end of the cylinder compartment 12.

Mounted on the top of the cylinder block is a head 16 which has joined cooling medium compartments 17 and 18. The compartment 17 communicates with the inlet passage 11 of the water jacket through registering apertures 19 and 20 in the head and jacket respectively. There are a plurality of these registering apertures distributed throughout the length of the head and jacket. Another series of registering apertures 21 and 22 are provided in the opposite side of the head 16 and jacket 5 respectively, in communication with the compartment 18 of the head.

Formed at the upper end of the webs 10 are apertures or ports 23 which permit some of the incoming cooling medium to flow through the partition from the inlet passage 11 into the cylinder compartment 12 of the jacket. These ports are located in close proximity to the valve seats 24 so as to subject the valve seats and the associated structure to the cooling action of the medium before its tempera-

ture is increased by contact with the cylinders. An outlet 25 on the front end of the head is connected by a tube 26 with the radiator 8.

In operation, the cooling medium is fed from the radiator 8 through the tube 9 into the inlet passage 11 of the water jacket by the rotor 7. Some of the medium passes through the ports 23 directly into the cylinder compartment 12 and some of the medium 10 passes upwardly through the registering apertures 19 and 20 into the compartment 17 and 18 of the head 16. The remainder of the medium flows rearwardly to the end of the jacket where it is admitted into the cylinder 15 compartment thereof. The cooling medium then progresses forwardly in this compartment and as it is heated by the cylinders, it rises and passes upwardly through the registering apertures 21 and 22 into the compartment 20 18 of the head 16 from which it flows back to the radiator 8 through the outlet 25 and tube 26.

Although but one specific embodiment of this invention has herein been shown and described, it will be understood that various changes including the size, shape and arrangement of parts may be made without departing from the spirit of my invention and it is not my intention to limit its scope other than by the terms of the appended claims.

I claim:

1. In an internal combustion engine comprising a plurality of cylinders and a plurality of valve sleeves, a cooling medium 35 jacket surrounding said sleeves and cylinders including a top wall having valve seats formed therein, webs between adjacent valve sleeves having apertures therein adjacent said top wall, and a cooling medium inlet 40 communicating directly with the space between said sleeves and the adjacent wall of said jacket for circulating some of the cooling medium through said apertures so as to bring the incoming cooling medium into contact with the portions of the top wall of said 45 jacket in which said valve seats are formed, the main part of said cooling medium being directed to the rear end of said engine and allowed to circulate forwardly past said 50 cylinders.

2. In an internal combustion engine a cooling medium jacket having an inlet and an outlet and including a top wall having valve seats formed therein; and a longitudinal partition in the interior of said jacket registering with the intermediate portions of said valve seats for providing a chamber in communication with said inlet to receive the incoming cooling medium and having apertures adjacent said top wall for permitting some of the incoming cooling medium to flow along and contact with that portion of the top wall in which the inner parts of said valve seats are formed.

3. In an internal combustion engine a cool-

ing medium jacket having an inlet and an outlet, a partition in the interior of said jacket providing a receiving chamber for incoming cooling medium communicating with said inlet and a main chamber, and valve seats formed in the structure of said engine and extending at least in part over said main chamber, said partition having spaced apertures therein adjacent the structure in which the valve seats are formed for bringing the 75 cooling medium from the receiving chamber directly into contact with the structure of the main chamber in which the valve seats are formed.
